UNITED STATES PATENT OFFICE.

WALTER M. OLIVER, OF PARSONS, KANSAS.

PULVERIZED-COAL-BURNING FURNACE.

1,257,103.

Specification of Letters Patent. Patented Feb. 19, 1918.

Application filed March 2, 1917. Serial No. 152,086.

To all whom it may concern:

Be it known that I, WALTER M. OLIVER, a citizen of the United States, residing at Parsons, in the county of Labette and State 5 of Kansas, have invented new and useful Improvements in Pulverized-Coal-Burning Furnaces, of which the following is a specification.

My invention relates to pulverized coal 10 burning furnaces and particularly to that class of pulverized coal burning furnaces to which the burnt coal is brought into contact with a current of air, and is mixed therewith, and carried in suspension with the air 15 into the combustion chamber of the furnaces where it is ignited and burned.

My invention has for its objects; first, to provide a device for properly intermixing pulverized coal and air whereby a mixture 20 of uniform density is procured secondly, to provide a means for regulating the amount of air which passes through the mixing device, and thirdly, to provide a device for intermixing pulverized coal and air, by which 25 the mixture will be delivered to the combustion chamber of the furnace in its most efficient form for burning.

With these and other objects in view which will be hereinafter fully described and particularly pointed out in the claims, the invention consists in the mechanism illustrated in the accompanying drawing forming a part of this specification and illustrating the preferred embodiment of my invention, in 35 which:—

Figure 1 is a partially sectional side elevation of a furnace embodying my invention.

Fig. 2 is an enlarged sectional side elevation of the air and coal mixing device.

Fig. 3 is a front end elevation of the same.

Fig. 4 is a view looking at the opposite end.

Like characters of reference indicate like parts in the various views.

In the drawings 1 designates a furnace adapted to burn a mixture of pulverized coal and air. Attached to the front wall 2 of 50 the furnace a mixing chamber 3 is provided. The mixing chamber, in the preferred embodiment illustrated, consists of a cylindrical inclosure having its ends open. The ends of the mixing chamber are designated 55 as in the drawings by 4 and 5, the end 4 being at the combustion end of the mixing de-

vice and the end 5 being at the outer or air inlet end of the mixing chamber. Leading into the outer or inlet end 5 of the mixing chamber a forced air draft pipe 6 is provided and is disposed concentrically of the said open end 5. Brackets 7 are disposed within the mixing chamber and hold said pipe 6 in proper position. Said pipe 6 terminates in the mixing chamber at a point 65 intermediate the ends thereof. The other end of said air pipe is flanged, as designated at 9, and is bolted to a flanged air supply pipe 10. The other end of said air supply pipe communicates with a fan or blower 11 70 of usual construction and which is employed to maintain a constant current of air through the mixing chamber as hereinbefore described.

A baffle plate is disposed within the mixing chamber and is composed of two members 12 and 13. The member 12 is horizontal and overlies the nozzle 8, leaving a passage 14 between it and the upper surface of the mixing chamber. The other member 80 13 of the baffle plate extends from the combustion end of the member 12 and extends outwardly toward the combustion end of the mixing chamber, the combustion end of member 13 being disposed at a lower plane 85 than its other end whereby said member 13 is positioned in the path of current of air passing through the nozzle 8. A passage 15 is provided between the combustion end of the member 13 and the lower surface of the 90 mixing chamber. Directly above the member 13 and extending at right angles to the member 12 is a fuel supply pipe 16, the outlet end of which extends through a hole in the side of the mixing chamber and projects 95 into said chamber some distance below the plane of the upper member 12. The other end of the fuel supply pipe 16 communicates with a hopper 17 of suitable construction for maintaining a flow of pulverized fuel 100 through the said pipe. An inspection hole 18 is provided in the mixing chamber whereby the interior of said chamber may be inspected. A flange 19 is provided on said mixing chamber surrounding the hole 18 105 and is adapted to engage a lid 20 whereby the hole may be closed.

Affixed to the mixing chamber at a point therein between the member 13 and the combustion end of the mixing chamber is a baffle 110 plate 21, which is preferably disposed upon said mixing chamber surface in line with

the passage 15. The said baffle plate 21 serves to constrict the combustion end of the mixing chamber whereby the mixture of air and pulverized fuel passing therethrough is compressed and a more intense flame is procured in the combustion chamber of the furnace.

It will be noted that the air inlet end 5 of the mixing chamber is open, being only 10 restricted by the concentrically disposed air intake pipe 6 as hereinbefore described. This opening is provided so that air may be admitted therethrough into the mixing chamber to either mix with the air issuing from 15 the nozzle 8 and flowing through the passage 15 or to flow through the passage 14 and mingle with the mixture after it has passed the member 13. A damper 22 is provided to close the opening at the outer end of the 20 mixing chamber. A screw threaded stud 23 is mounted upon the mixing chamber and extends outwardly therefrom and engages the ear 24 of the damper 22. Wing nuts 25 are provided and are screw threaded upon 25 the stud 23 and are adapted to clamp the ear 24 between them thereby holding the damper in place. The damper may be adjusted by loosening the wing nuts and moving the damper along the air pipe 6 to the proper 30 position and clamping it thereby by means of said wing nuts.

In the operation of the device coal passes through the fuel supply pipe 16 and drops down upon the member 13 where it is scattered about thereon. By reason of the slanting surface of the baffle plate and the draft induced in the mixing chamber by air being forced through the nozzle 8, the pulverized fuel moves down upon the surfaces of said 40 member 13 until it reaches the lower edge thereof. The air current passing under the lower edge of said member 13 picks up the fuel dropping therefrom and holds the same in suspension as it travels toward the combustion end of the mixing chamber. By 45 reason of the fact that the coal is spread over the surface of the member 13 and is picked up by the air current when in a scattered condition, a complete and uniform

mixture of the air and coal is obtained. As 50 the mixture passes through the combustion end of the mixing chamber it is restricted by means of the baffle plate 21, hereinbefore described, and issues from said combustion end of the mixing chamber in this condition. 55 The mixture is ignited in the combustion chamber of the furnace and produces an intense heat therein.

It will be noted that by the above description the flow of air may be varied by means 60 of the damper 22 independently of the forced draft issuing through the nozzle 8. By this arrangement the flow of air admitted may be varied without interfering with the mixing functions of the device. This aids materially in obtaining a proper proportion of air and coal whereby an intense heat may be generated under various conditions and with a minimum amount of coal.

Having thus fully described my invention, 70 I claim:

1. In a device of the character described, a mixing chamber comprising an elongated casing open at both ends, an air draft extending within said casing, an inclined baffle 75 plate located within said casing and extending entirely across the open inner end of said air draft and means for projecting pulverized fuel upon said baffle plate.

2. In a device of the character described, 80 a mixing chamber comprising an elongated casing open at both ends, an air draft extending within said casing, an inclined baffle plate located within said casing and extending 85 entirely across the open inner end of said air draft, means for projecting pulverized fuel upon said baffle plate and a second inclined baffle plate, said second baffle plate being inclined in a direction opposite to the first mentioned plate and beginning at a point 90 in vertical alignment with and below said first mentioned plate and extending upward to the discharge end of the mixing chamber, whereby the opening of the discharge end of the mixing chamber is restricted.

In testimony whereof I affix my signature,
WALTER M. OLIVER.
